UNITED STATES PATENT OFFICE

2,385,561

MERCURY ARC DEVICE

Leonard M. Wittlinger, Flint, Mich., and William S. Brian, Owemboro, Ky., assignors to General Motors Corporation, Detroit, Mich., a corporation of Delaware

Application August 30, 1943, Serial No. 500,486

10 Claims. (Cl. 315—56)

This invention relates to mercury arc means and more specifically to mercury arc means as a source of luminescent rays. There have recently been a number of instances in which it is desirable to provide and utilize rays of the ultraviolet type for various purposes, such as, for example, the use of a mercury arc generator of ultraviolet rays whereby the same may be projected in a beam either to locate objects covered with luminescent material, such as road markers so that field maneuvers may be made under cover of darkness without disclosing such movement to the enemy, or signaling between points, using such ultraviolet or substantially invisible rays projected in a beam from one point to another which would not be discernible for enemy interception. These are, of course, only two examples; many other uses are to be found for such equipment.

It is therefore an object of our invention to provide a satisfactory source for ultraviolet rays.

It is a further object of our invention to provide a relatively small tube capable of generating rays of ultraviolet wave length.

It is a still further object of our invention to provide a mercury arc tube in which the inner surface is not discolored after periods of operation.

With these and other objects in view, which will become apparent as the specification proceeds, the embodiments of our invention will be best understood by reference to the following specification and claims and the illustrations in the accompanying drawing, in which:

Figure 1 shows a vertical section through a tube embodying one form of our invention; and

Figures 2, 3, 4 and 5 are similar vertical sections showing different modified forms of our invention.

The general type of tube disclosed herein is that having in reality two different sections: a low voltage and a high voltage section, the low voltage providing an automatic interrupter pair of electrodes which periodically and successively interrupt a low voltage circuit, and the second or high voltage portion embodying an electrode capable of drawing an arc from the upper surface of a mercury pool, which latter portion of course provides the main source for ultraviolet rays. This general type has been disclosed in a patent to Brian, No. 2,289,623, issued July 14, 1942, and entitled "Mercury light tube." However, in the earlier forms of this device it was found that the inner surface of the envelope which enclosed the arc section began to darken after the

tube had been in use for a little time. After some study as to what caused this darkening, which of course interfered considerably with the amount of ultraviolet rays transmitted through the tube, it was determined that this was due to small particles of carbon eroded away from the carbon electrode of the interrupter section of the tube which floated to the top of the mercury pool and were then splattered onto the inner surface of the tube by the arc. In an effort to prevent these small eroded carbon particles from reaching the upper surface of the mercury pool, the present constructions were evolved.

Referring now more specifically to Figure 1, there is shown therein an enclosing envelope 2 which carries at its upper end a sealed-in electrode 4 and in one side a second electrode 6. A third electrode 8 is supported in the lower portion of the envelope and is stacked into a small carbon disc 10 forming the lower electrode of the interrupter section. Surrounding this carbon electrode 10 is a small ceramic disc 12 rigidly supported in the interior of the envelope. A second internal envelope 14 integral with the base of the outer envelope 2 and substantially concentric with and spaced from the vertical portion extends up approximately one-half the full length of the interior and totally encloses the ceramic disc and carbon electrode 10. In one side of this inner envelope there is provided an opening 16 whereby the mercury 18 in the large envelope may flow in and out of the inner envelope entirely covering the same and extending up a substantial distance above the upper end to within a relatively short distance of the lower end of the electrode 4. A small up-turned tube 20 is supported within the inner envelope 14 and extends up above the opening 16 to provide a baffle for the carbon particles as they ascend in the mercury.

Through the exterior circuit between electrodes 6 and 8, which is fully disclosed in the above identified patent, low voltage power is supplied to the tube and current flows between them from electrode 6 through the mercury bath 18 between the large and small envelopes through the mercury in the opening 16 through the mercury within the inner envelope 14 to the carbon electrode 10 and thus to the electrode 8. As described in the patent, when this current intensity is sufficient to heat the mercury in contact with the carbon 10, that mercury vaporizes and flashes off the surface of the carbon electrode to interrupt the circuit. Whereupon, since the source of heat has now disappeared, the mercury vapor condenses to reform the same, thus

providing an automatic continuous interruption.

In this operation, however, the upper surface of the mercury begins to erode and small particles of the carbon are broken away, and since they are lighter than mercury, tend to rise to the surface of the mercury pool. Thus they ascend through the small tube 20 to eventually contact the upper inner surface of the inner envelope 14 and are unable to reach the upper surface of the mercury 18 from which an arc is drawn to the upper electrode 4. Thus the upper surface of the mercury will be kept clean from any small carbon particles and the inner surface of the glass will not discolor but will remain clear and transmit a maximum portion of the ultraviolet rays generated by the arc over a long period of time.

Figure 2 shows a second form of trap for preventing the small carbon particles from rising to the upper surface or arc surface of the mercury. In this instance the same main electrodes 4, 6, 8 and 10 are present in their same respective positions. The envelope 2' in this case, however, supports a larger ceramic disc 12' in its base and has extending across slightly below the middle a bulbous or spherical baffle 22 which is supported by the sides of the envelope and extends entirely between them. One side of this spherical baffle has an opening 24 therein through which mercury 18 can flow from the upper portion of the envelope to the lower portion. This opening, however, is directed downward from the horizontal and is considerably below the top of the spherical ball 22. In like manner, any carbon particles eroding from the electrode 10 which tend to rise to the top of the mercury will be trapped in the upper portion of the spherical ball 22 and will be prevented from reaching the upper surface of the mercury 18 from which the electrode 4 draws an arc.

Figure 3 shows a further modified form which is substantially the same as Figure 2 except that instead of a spherical baffle across the envelope, one of a substantially pyramidal form is utilized. As shown in this figure, the pyramidal baffle 26 is shown extending between the two side walls of the envelope 2'' and in this instance is much lower than that in Figure 2, the base of the pyramid being substantially in alignment with the upper surface of the disc 12'. A small opening 28 is provided in the side of the pyramid for inter-connection of the mercury outside and inside the baffle portion. Its action of course is the same as that previously described.

In Figure 4 there is shown a still further modification in which a small cylindrical housing 30 is shown immediately over the carbon electrode, said cylindrical housing terminating in a semi-spherical dome 32 for the collection of the carbon particles and being mounted directly on the upper surface of a base 34 which surrounds and holds in place the carbon electrode 10. The lower portion of the housing 30 is slotted as shown at 36 to allow mercury to flow in through the slots and also is provided with an opening 38 on one side to further allow inter-communication between the two mercury pools. In this instance, of course, the small carbon particles eroding from the upper surface of electrode 10 will be trapped in the dome-shaped portion 32 of the housing.

Figure 5 shows quite a different form in which the envelope 2''' is separated into two major portions by a spherical baffle 40, thus providing an upper and a lower chamber. In the lower chamber there are two main electrodes 6' and 8', the latter being electrically connected to a long car-

bon electrode 10' extending up into the chamber and surrounded by glass sleeve portion 42 eventually terminating in a beveled face 44. This chamber is filled with a mercury pool 46 which completes the electrical circuit from the beveled face 44 to the electrode 6' to provide interrupter action. Mounted on the upper central surface of the spherical baffle 40 and within the upper chamber so provided is a second cylindrical housing 48 of smaller diameter than the outer envelope 2''' and spaced from its inner surface. Within this housing 48 there is a small mercury pool 50 which of course resides in the lower portion, and extending through from the interior of the housing 48 to the interior of the lower section of the envelope 2''' is a metallic conducting electrode 52 adapted to contact both mercury pools 50 and 46 and to conduct current from one to the other.

The upper portion of the envelope 2''' supports as before an electrode 4 which in this case extends down into the interior cylindrical member 48 to a definite spaced distance from the small mercury pool 50. Since therefore the two sections of the tube are now definitely separated into an interrupter portion and an arc portion, no carbon particles from the surface 44 can possibly be carried up to the upper or arc portion within the housing 48 and therefore the coating or darkening of the internal surface thereof through the splattering of carbon particles will be eliminated. The arc will be drawn in this instance between electrode 4 and mercury pool 50 which is in conductive relation with electrode 6' through contact rod 52 and mercury pool 46.

We claim:

1. In a device of the class described, a housing, a carbon electrode supported in the housing, a mercury pool partially filling the housing in contact with said electrode and forming a part of the circuit therewith and baffle means to trap carbon particles eroded away from the carbon electrode through use and stop them from reaching the upper surface of the mercury pool.

2. In a device of the class described, a housing, a carbon electrode supported in the housing, a mercury pool partially filling the housing in contact with said electrode and forming a part of the circuit therewith, and spherical baffling means mounted in the housing below the surface level of the mercury trapping any eroded carbon particles from the carbon electrode and stopping them from rising to the surface of the mercury.

3. In a device of the class described, a housing, an electrode formed of a material which erodes away in small particles upon current flow therethrough supported by said housing, a mercury pool partially filling the housing in contact with said electrode and forming a part of a circuit therewith and trapping means carried by said housing to stop any eroded electrode particles from reaching the surface of the mercury pool.

4. In a device of the class described, a hollow envelope of insulating material, a body of mercury partially filling said envelope, an electrode in the lower portion of said envelope in contact with the mercury which electrode erodes away upon usage whereby small particles thereof will tend to rise to the surface of the mercury and spherical baffling means across the envelope below the surface of the mercury to trap said particles and stop them from getting to the surface of the mercury.

5. In a device of the class described, a hollow envelope of insulating material, a plurality of

electrodes in one portion of the envelope, one of which electrodes is formed of carbon, a pool of mercury partially filling said envelope and completing the circuit between the electrodes to form an interrupter therewith, a further electrode supported in the envelope in spaced relation to the mercury and adapted to draw an arc from the mercury surface and baffling means trapping particles of carbon eroded from the carbon electrode due to interrupter current flow.

6. In a device of the class described, a hollow envelope of insulating material, a plurality of electrodes in one portion of the envelope, one of which electrodes is formed of carbon, a pool of mercury partially filling said envelope and completing the circuit between the electrodes to form an interrupter therewith, a further electrode supported in the envelope in spaced relation to the mercury and adapted to draw an arc from the mercury surface, and baffling means across the envelope below the surface of the mercury to trap eroded carbon particles.

7. In a device of the class described, a hollow envelope of insulating material, a plurality of electrodes in one portion of the envelope, one of which electrodes is formed of carbon, a pool of mercury partially filling said envelope and completing the circuit between the electrodes to form an interrupter therewith, a further electrode supported in the envelope in spaced relation to the mercury and adapted to draw an arc from the mercury surface, and spherical baffling means across the envelope below the surface of the mercury having an opening therethrough below the top portion whereby eroded carbon particles are trapped in the concave top and a continuous mercury connection is provided through the opening.

8. In a device of the class described, an envelope of insulating means, a pair of electrodes 40

supported in spaced relation in one part of the envelope, one of said electrodes being formed of carbon, a pool of mercury in the envelope bridging the electrodes and forming therewith an interrupter, a third electrode supported in a further portion of the envelope and providing arcing means and baffling means trapping eroded carbon particles from the interrupter section to stop them from reaching the arc section and being splattered onto the envelope surface to darken the same.

9. In a device of the class described, an insulating envelope, a partition dividing the envelope into two chambers, a pair of electrodes supported in spaced relation in one chamber, one of said electrodes being formed of carbon, a pool of mercury in said first chamber bridging said electrodes to form therewith an interrupter, a third electrode supported in the second chamber and conductive means extending through the partition to carry current from the first to the second chamber to cooperate with the third electrode to form an arc therewith.

10. In a device of the class described, an insulating envelope, a partition dividing the envelope into two chambers, a pair of electrodes supported in spaced relation in one chamber, one of said electrodes being formed of carbon, a pool of mercury in said first chamber bridging said electrodes to form therewith an interrupter, a third electrode supported in the second chamber, conductive means extending through the partition to carry current from the first to the second chamber to cooperate with the third electrode to form an arc therewith and a small body of mercury in the second chamber to form part of the circuit between the third electrode and the conductive means.
